UNITED STATES PATENT OFFICE.

ROGER W. CONANT, OF BOSTON, MASSACHUSETTS.

RAIL-JOINT-TESTING APPARATUS.

SPECIFICATION forming part of Letters Patent No. 645,384, dated March 13, 1900.

Application filed November 13, 1899. Serial No. 736,747. (No model.)

To all whom it may concern:

Be it known that I, ROGER W. CONANT, a citizen of the United States, residing in Boston, in the county of Suffolk and State of Massachusetts, have invented an Improvement in Rail-Joint-Testing Apparatus, of which the following description, in connection with the accompanying drawings, is a specification, like letters and figures on the drawings representing like parts.

This invention relates to an apparatus for rapidly and efficiently measuring electrical resistances, and especially very low resistances, such as the resistance of rail-joints in the tracks of electric-railway systems.

In accordance with this invention I employ three portable circuit-terminals, two of which are adapted to make contact with the conductor to be measured and the other of which is adapted to be connected with a known or computable resistance in circuit with the unknown resistance. The intermediate or central portable circuit-terminal is connected in circuit with the other two circuit-terminals through a telephone-receiver, so that the line including said telephone forms part of two distinct metallic circuits, whereby sounds produced at the telephone by the making or breaking of one circuit may be compared with the sounds produced by the making or breaking of the other circuit and whereby said sounds may be balanced or rendered substantially the same by changing one of the outside circuit-terminals with relation to the circuit-terminal connected with the telephone. In this manner a comparative means is provided for measuring the resistance included in one circuit between the central terminal and one of the outside terminals. The telephone-circuit may and preferably will include in it a circuit-interrupter, preferably a break-wheel operated by a clock mechanism, and said telephone and circuit-interrupter may be carried by a suitable box or case, which, preferably, also contains a coil and a resistance connected in shunt-circuit with the telephone, which shunt-circuit is controlled by a switch located on the outside of the box or case of the instrument. The two independent or distinct circuits are adapted to be controlled by a switch or circuit-controller carried by the box or case and readily accessible, so that it may be thrown or moved substantially in an in-

stant to include the telephone first in one and then in the other of said circuits to make the comparison of sounds desired, and which switch or circuit-controller in its normal or central position connects the telephone with both circuits, so that if the resistance included between the central portable terminal and one outside terminal is equal to the resistance between the central terminal and the other outside terminal then the telephone will remain silent upon interruption of its circuit.

The invention, as above described, is particularly well adapted for measuring low resistances, such as the rail-joints of the tracks of electric railways, without the use of current other than that derived from the track and employed in the car-service, the resistance of the rail-joint being made known by the length of the rail between the central portable terminal and the outside terminal on the same side of the joint being measured.

These and other features of this invention will be pointed out in the claims at the end of this specification.

Figure 1 is a perspective view of a box or case forming part of an apparatus embodying this invention; Fig. 2, a front elevation of the box or case shown in Fig. 1 with its cover raised and its front side partially broken away; Fig. 3, a plan view of the box or case with its cover removed; Fig. 4, an elevation of one of the portable circuit-terminals adapted to make contact with the rail and to be connected with the box or case shown in Fig. 1; Fig. 5, a diagram of circuits, to be referred to, which illustrates the operation of the invention.

In the present instance I have shown what I regard as the most efficient form of apparatus for effecting the object desired. Referring to Fig. 1, *a* represents a box or case provided with a cover *b* and with a strap *c*, which is adapted to be passed over the shoulders of the operator, thereby leaving both hands of the operator free to work the apparatus. The cover *b* is provided on its upper face with two terminal plates *d e*, having their ends substantially close together and adapted to be bridged or connected by a movable switch-lever *f*, which is also capable of making contact separately with either of the terminals *d e*. The cover *b* also has pivoted to it a switch-lever *g*, adapted to coöperate with

a series of terminals or buttons *h*, for a purpose as will be described. The box or case *a* on its front side has connected to it three binding-posts *i j k* and has pivoted to it on 5 the same side a lever *m*, adapted to make contact with a circuit terminal or button *n*. The box or case *a* on one end (see Fig. 3) is provided with binding-posts *o p*, with which are adapted to be connected wires *q r*, leading to a telephone-receiver *s* of any suitable or usual construction. The box or case at its opposite end, as shown in the present instance, is provided with a lever *t*, adapted to coöperate with the terminal *u*. The box or 15 case, as shown in Fig. 3, is subdivided by partition-walls 2 3 4 into compartments 5, 6, 7, and 8, the walls 2 4 being preferably made removable and the compartments 5 8 being designed and adapted to contain duplicate 20 circuit-breakers, only one of which is shown and which may and preferably will consist of a break-wheel 9, operated by a clock mechanism 10 of any suitable or usual construction, and with which coöperates a contact-spring or 25 terminal pen 12, mounted on an insulating-block 13, fast to the framework of the clock 10, the clock mechanism being suitably attached to the partition-wall 4, so as to be removed therewith for repairs or other purpose and 30 preferably bearing against sound-damping material interposed between said clock and partition. The clock mechanism 10 is adapted to be wound by a suitable key 14, extended through a suitable hole in the front side of the 35 case, and the break-wheel is adapted to be held at rest by means of a spring-arm 15, fastened to the inner side of the box or case and normally engaging the shaft or pivot of the escapement-fan 16. The spring-arm 15 has extended 40 through it the pivot 17 for the lever *m* and is adapted to be disengaged from the pivot or shaft of the escapement-fan 16 when the lever *m* is thrown into engagement with the terminal *n*, which latter forces the lever *m* outward and draws the spring-arm 15 away from 45 the escapement-shaft, the button or terminal *n* acting in this case like a cam. The terminal pen or brush 12 in the present instance is included in circuit with the telephone *s*, and 50 the switch *m* is likewise included in the said circuit, the terminal pen or brush being connected with the central binding-post *j* by the wire 20. The spring-arm 15 is connected by wire 19 with the clock-frame. The outside 55 binding-posts *k i* are connected within the box by wires 21 22 (see Fig. 5) to the terminals *d e*, and the lever *f* is connected by wires 24 25 with the binding-post *p*, and the wire 24 is connected by wire 26 to the switch-lever *g*, 60 coöperating with the terminals *h*, to which is connected the resistance 27, and also coöperating with a blank terminal or button *u*, one of the terminals *h* being connected by wire 28 to a coil 29, which is connected by 65 wire 30 to the wire 31, connected with the binding-post *o*, the wire 31 being joined by wires 32 33 to the terminal *n*. The binding-

posts *i j k* are adapted to have connected to them the flexible conductors 40 41 42, connected with portable circuit-terminals, three 70 in number and marked 43 44 45 in Fig. 5. The circuit-terminals are and may be of like construction and preferably the same as that shown in Fig. 4, the same consisting of an edge-tool 46, adjustably secured, as by a set-screw 75 47, in a metal holder 48, provided with a handle 49, of wood or other suitable material, which is preferably provided, as herein shown, with a groove 50, in which the conductor is 80 laid.

In Fig. 5 I have shown two rails 50 51, making the joint 52, the resistance of which it is desired to test. For this purpose the box or case *a* and one portable circuit-terminal, as 43, are carried by the operator making the 85 test, while the other portable circuit-terminals 44 45 are carried by an assistant.

In operation the assistant places the terminals 44 45 in contact with the rails 50 51 on equal sides of the joint 52, and when thus 90 placed the operator carrying the box moves the switch-lever *f* onto the terminal *d* and then sets the circuit-breaker in operation by moving the lever *m* onto the terminal-button *n* and, preferably, also moves the switch-lever *g* onto the first terminal *h*, so as to include the coil 29, which I prefer to designate as the "kicking-coil," the office of which is to intensify the sound at the telephone *s*, which sound is produced in the present instance by 95 the break in the telephone-circuit. The circuit through the telephone may be traced as follows: from the portable terminal 45 to binding-post *k* by wire 42, thence by wire 21, terminal *d*, switch *f*, wires 24 25 *r* to telephone *s*, thence by wires *q* 31 32 33 to switch-lever *m*, wire 19 to break-wheel 9, thence by pen 12, wire 20 to binding-post *j*, and thence by wire 41 and terminal 44 to rail 50. Having obtained the sound given by interrupting the 100 circuit, including the rail-joint, the operator brings the portable terminal 43 into engagement with the rail 50 and throws the lever *f* over onto the terminal *e*, and the break-wheel 9 continuing to run will give a sound at the 105 telephone varying in intensity, according to the length of the rail 50 between the terminals 43 44, and by moving the terminal 43 toward or from the terminal 44, so as to vary the length 110 of the rail included in the telephone-circuit, the sound at the telephone is made equal to or substantially equal to the sound produced when the rail-joint is in circuit with the telephone. The circuit through the telephone, including the terminal 43, may be traced as 115 follows: from the terminal 43 by wire 40 to binding-post *i*, thence by wire 22, terminal *e*, switch-lever *f*, wires 24 25 *r* through the telephone *s*, thence by wires *q* 31 32 33, lever *m*, wire 19, break-wheel 9, pen 12, wire 20 to 120 binding-post *j*, and thence by wire 41, terminal 44, and rail 50 to terminal 43. It will thus be seen that by moving the lever *f* first onto the terminal *d* and then onto the terminal *e* the 125

- sounds may be quickly compared, so that by moving the terminal 43 along the rail 50 the said sounds may be rendered substantially equal or balanced, and when this point has been reached it may be tested by moving the switch *f* to its central position and so as to connect the terminals *d e* together, in which position if the resistance of the rail between the terminals 43 44 equals the resistance of the rail-joint the telephone will remain silent when its circuit is broken. The resistance of the track per foot in length is known, and the resistance of the joint is made known by the length of the rail between the terminals 43 44.
- 15 I prefer to use the kicking-coil 29; but an induction-coil may be used in place thereof, or the kicking-coil could be omitted when a low-resistance telephone-receiver is used. The kicking-coil is preferred, as it concentrates the available energy on the break in the telephone-circuit and practically no sound is obtained on the make, thereby increasing the sensitiveness of the instrument.
- 20 The resistance 27 is preferred, as it may be used to regulate or diminish the sound on strong track-currents.
- 25 The apparatus herein described is especially efficient in measuring very low resistances.
- 30 I have herein described one use to which the apparatus is particularly well adapted; but I do not desire to limit my invention in this respect, as it may be used to measure other resistances than those specified.
- 35 I prefer to employ the break-wheel and motor mechanism therefor and the switch *f*; but I do not desire to limit my invention in this respect, as they may be omitted, and sounds produced in the two circuits by lifting the terminals 43 45 from the conductors with which they are engaged and the silent test obtained by lifting the central terminal.
- 40 In the diagram Fig. 5 I have shown a duplicate break-wheel and motor mechanism which in practice may be secured to the partition-wall 2 and located in the compartment 5, so that in case of accident to the motor mechanism for the break-wheel in compartment 8 the duplicate apparatus in compartment 5 may be used at once, thereby avoiding delays in the work.
- 45 In practice the resistance of the wires between the terminal 43 and switch-terminal *e* should be made equal to the resistance of the wire between terminal 45 and switch-terminal *d*.
- 50 By the term "kicking-coil" I mean a self-inductive coil.
- 55 I claim—
- 60 1. In an apparatus of the character described, the combination with two independent metallic circuits having a conductor common to both, and a telephone-receiver in the common conductor, substantially as and for the purpose specified.
- 65 2. In an apparatus of the character described, the combination with two independent metallic circuits having a conductor common to both, a telephone-receiver and a circuit-interrupter in the common conductor, substantially as described.
- 70 3. In an apparatus of the character described, the combination with two independent metallic circuits having a conductor common to both, a telephone-receiver and a circuit-interrupter in the common conductor, and a switch in circuit with said telephone cooperating with both of said independent circuits, substantially as described.
- 75 4. In an apparatus of the character described, the combination with two independent circuits having a conductor common to both, a telephone-receiver in the common conductor, a shunt-circuit for said telephone provided with a kicking-coil, substantially as described.
- 80 5. In an apparatus of the character described, the combination with two independent circuits having a conductor common to both, a telephone-receiver in the common conductor, a shunt-circuit for said telephone provided with kicking-coil, and with a resistance, and a switch in said shunt controlling said resistance.
- 85 6. In an apparatus of the character described, the combination with two independent circuits having a conductor common to both, a telephone-receiver in said common conductor, a break-wheel in said common conductor, and a motor mechanism to operate said break-wheel, and means to control the said motor mechanism, substantially as and for the purpose specified.
- 90 7. An apparatus for measuring electrical resistances by a comparison of sounds produced in a circuit including the resistance to be measured with sounds produced in a circuit including a known resistance, it comprising movable terminals adapted to make contact with the resistance to be measured, conductors connected to said terminals, a telephone connected to one of said conductors, a third movable terminal adapted to be connected with a known resistance and connected with the conductor to which the telephone is connected, the said third movable terminal being movable toward and away from the terminal for the telephone, substantially as described.
- 95 8. In an apparatus of the character described, the combination with a telephone-receiver, a circuit-breaker in the telephone-circuit, a shunt-circuit for said telephone between the telephone and said circuit-breaker, and a kicking-coil in said shunt to intensify the sound at the telephone, substantially as described.
- 100 In testimony whereof I have signed my name to this specification in the presence of two subscribing witnesses.
- 105 ROGER W. CONANT.
- 110 Witnesses:
- 115 JAS. H. CHURCHILL,
J. MURPHY.
